(57) **CLAIM**

The ornamental design for a support board for mouse and keyboard, as shown and described.

DESCRIPTION

FIG. 1 is a perspective view of a support board for mouse and keyboard showing my new design;

FIG. 2 is a top plan view thereof;

FIG. 3 is a side elevational view thereof, the opposite side view being a mirror image of that shown;

FIG. 4 is a front view thereof;

FIG. 5 is a rear view thereof;

FIG. 6 is a cross sectional view taken along line 6—6 of FIG. 4; and,

FIG. 7 is a cross sectional view taken along line 7—7 of FIG. 4.

The undisclosed bottom side of the support board is plain and substantially unadorned.
